(57) **CLAIM**

The ornamental design for a correction tape applicator, as shown and described.

DESCRIPTION

FIG. 1 is a perspective view of a correction tape applicator according to the present invention;

FIG. 2 is a right side elevational view thereof;

FIG. 3 is a left side elevational view thereof;

FIG. 4 is a top elevational view thereof;

FIG. 5 is a bottom elevational view thereof;

FIG. 6 is a rear elevational view thereof; and,

FIG. 7 is a front elevational view thereof.

The broken line showings in the Figures are for illustrative, environmental purposes only and form no part of the claimed design.
